STOCKING PROTECTOR

Delma Crichton, New York, N. Y.

Application May 12, 1938, Serial No. 207,427

3 Claims. (Cl. 36-2)

This invention relates to stocking protectors and has for an object to provide a construction which may be easily applied and easily removed and which when in use will cover all the exposed parts of a woman's stocking.

Another object of the invention is to provide a protecting device for stockings which may be folded into a small package and carried by a woman in her hand-bag, and may be readily unfolded and placed in position over stockings being worn.

A further object, more specifically, is to provide a stocking protector which is substantially transparent and which when placed over a stocking when worn will be held in position at the upper end by a suitable elastic and at the lower end by a shoe strap.

In the accompanying drawing—

Fig. 1 is a view slightly in perspective showing an embodiment of the invention as it will appear in use;

Fig. 2 is a perspective view of the protector shown in Fig. 1, the same being on an enlarged scale;

Fig. 3 is a transverse sectional view through Fig. 2, approximately on the line 3-3;

Fig. 4 is a fragmentary vertical section taken on an enlarged scale through Fig. 2, approximately on the line 4-4;

Fig. 5 is an enlarged fragmentary sectional view through Fig. 2, approximately on the line 5-5.

Referring to the accompanying drawing by numerals, 1 indicates the protector as a whole, and 2 a stocking as it appears when in use. As indicated in Fig. 3, there is illustrated a shoe 3 in connection with the leg shown so that when the protector 1 is in use the shoe strap 4 may be properly fitted under the arch of the shoe and the retaining elastic strap 5 fitted around the small part of the leg immediately below the knee. Preferably the straps 4 and 5 are elastic and are stitched in place at both ends.

The protector 1 is preferably appreciably larger than the leg of the person wearing the device so that it may be readily slipped in place, but by reason of the elastic strap 5 the band 6 will properly grip the leg to support the protector. The protector 1 is provided with a body 7 which may be made from any suitable material but preferably from a transparent material, such as oil silk, though other substantially waterproof material may be used without departing from the spirit of the invention. The band 6 is formed with a substantially inelastic strip 8 held in place by

stitching 9 which extends through the folded-over portion 10 of the upper edge of the body 7. Preferably the elastic band member 5 is held in place by special stitching 11 at the respective ends and with the band 6 forms a completely encircling 5 band member.

It will be noted from Figs. 1 and 2 that the body 7 is cut away at 12 and is turned over and stitched to provide hems 13 and 14 which merge into a single hem 15 extending from the opening 12 to the bottom of the protector. Also the protector at the lower end is preferably folded upon itself several times, as indicated in Fig. 4, to make a stiffening cuff 16. Suitable lines of stitching 17 act to hold the folded portions together 18 and also connect the arch band 4 in place.

When the device is to be used the foot with the shoe 3 is inserted through the top of the protector and then the protector is pulled upwardly until it reaches the position shown in Fig. 1. 20 This is done for each leg and, consequently, stockings will be properly protected against rain, snow, and the like. When the rain, snow, or the like, has ceased, the protector may be readily removed by reverse movement to that above described. 25 The protector is easily folded into a very small package and may be stored in the usual hand-bag carried by women.

I claim:

1. A stocking protector comprising a flexible 30 body having a stiffening cuff at one end and a band at the opposite end, said band having a non-elastic section secured to said body and an elastic section having its ends connected to the ends of said non-elastic section, said band being 35 of a size to snugly fit against the leg of the wearer, said body being substantially tubular and of a size to readily fit over the leg of a person, and an elastic arch strap connected to said cuff positioned to extend beneath the shoe of the person 40 wearing the protector for elastically holding the protector against rising independently.

2. A stocking protector for protecting stockings against snow, rain, and the like, provided with a flexible tubular body open at both ends and provided with an inclined cutaway portion at the top end, a band member at the top of said protector, said band member comprising a non-elastic section stitched to the top end of said body and an elastic strap having its ends connected to said 45 non-elastic section and extending outwardly beyond the non-elastic section across said cutaway portion to act with the non-elastic section as an encircling band to grip the leg immediately below the knee when the protector is in use, and an 50 55

elastic strap at the lower end of the body adapted to fit beneath the foot of the person wearing the protector for resiliently holding said body against rising independently.

- 5 3. A stocking protector comprising a tubular body of flexible substantially waterproof material, means forming a band at the top of said body, said means having a substantially non-elastic section, stitching for securing said non-elastic section to the top portion of said body and an elas-

tic member secured at its respective ends to the respective ends of said elastic section, said body being folded upon itself at the end opposite said band to form a reinforcing and stiffening cuff, a line of stitching for holding said folded portions together, and a substantially U-shaped elastic arch strap secured at its ends by said line of stitching to opposite sides of said body. 5
